(57) **CLAIM**

The ornamental design for a bookrack, as shown and described.

DESCRIPTION

FIG. 1 is a front isometric view of a first embodiment of a bookrack for use with a classroom chair;

FIG. 2 is a front perspective view of the bookrack separate from the classroom chair;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a front isometric view of a second embodiment of a bookrack for use with a classroom chair;

FIG. 10 is a front perspective view of the bookrack separate from the classroom chair;

FIG. 11 is a top plan view thereof;

FIG. 12 is a bottom plan view thereof;

FIG. 13 is a front elevation view thereof;

FIG. 14 is a rear elevation view thereof;

FIG. 15 is a right side elevation view thereof; and,

FIG. 16 is a left side elevation view thereof.

The broken lines shown in the drawing views are included for purposes of illustrating environment and form no part of the claimed design.

1 Claim, 10 Drawing Sheets
